UNITED STATES PATENT OFFICE.

SILAS ALBERT DIXON AND SAMUEL LYNN RATLIFFE, OF GADSDEN, ALABAMA.

SANITARY DRY CLOSET.

1,250,701.

Specification of Letters Patent. Patented Dec. 18, 1917.

Application filed September 17, 1917. Serial No. 191,861.

To all whom it may concern:

Be it known that we, SILAS ALBERT DIXON and SAMUEL LYNN RATLIFFE, citizens of the United States, residing at Gadsden, in the county of Etowah, State of Alabama, have invented a new and useful Sanitary Dry Closet, of which the following is a specification.

The subject of this invention is a sanitary dry closet, and the objects of the invention are, first to provide a sanitary dry closet with a receptacle which may be easily removed from and returned to the closet, second, to provide a novel means for detachably holding the receptacle in place, third, to provide a tight joint between the receptacle and the seat, fourth, to provide a simple and efficient dry closet.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

A practical embodiment of the invention is shown in the accompanying drawing, wherein:

Figure 1 is a central vertical longitudinal section of a closet constructed in accordance with the invention.

Fig. 2 is a central, vertical cross section of the same.

Referring to the drawing by numerals of reference:

The usual and ordinary casing and housing is indicated at 1, and this casing may be provided with a door 2 to normally close the casing. A seat or top 3 formed with a suitable opening 4 is provided and a lid 5 may be secured to the seat by hinges 6 for the purpose of normally closing the opening 4.

Secured to the under side of the seat or top 3, and to each side thereof, are guide strips 7 formed with opposed flanges 8. The flanges 8 are adapted to receive and support the flanges 9 which extend from the

upper edge at each side of a receptacle or bucket 10. The bucket 10 has lugs or ears 11 secured at each side thereof to which are pivotally connected the ends of a handle 12. 55 A hand grip 13 may be rigidly secured to the rear of the receptacle to aid in withdrawing the receptacle from the casing.

Secured to the under side of the seat 3 is a plate of resilient metal 14 the front edge 60 15 of which is secured to the under side of the seat 3 and may be bent as shown to provide a stop for the bucket or receptacle 10. It is of course understood that a separate piece may be provided for this stop if desired. 65

The side edges of the plate 14 rest in the space between the lower face of the seat 3 and the flanges 8, as seen most clearly in Fig. 1. The rear edge of the plate 14 is bent 70 as shown in Fig. 2 to provide a latch 16 which engages the rear upper edge of the receptacle 10. The rear edge is extended outwardly and upwardly to be easily accessible to one wishing to withdraw the receptacle. The plate 14 is provided with an opening 17 which aligns with the opening 4 of the seat. 75

A vent pipe 18 may be mounted in a suitable aperture in the seat 3 and a gauze partition 19 may be secured in this pipe to keep flies from entering the receptacle 10. 80

In practice the device operates as follows: The resilient plate 14 presses down upon the side flanges 9 of the receptacle and 85 retains them firmly seated on the flanges 8 while the upturned rear edge of the plate 14 contacts the rear edge of the seat 3 thereby effectually closing all ingress to the receptacle 10. When it is desired to remove the 90 receptacle, the door 2 is opened, the rear edge of the plate 14 pressed upwardly to release the latch and the receptacle drawn out.

Having thus described the invention, what is claimed as new and sought by Letters 95 Patent, is:

1. A sanitary dry closet, comprising a seat, guides on the under side of the seat, opposed flanges on the guides, a receptacle, flanges on the receptacle and adapted to be seated 100 on the flanges of the guides, a resilient plate secured to the seat and overlying the flanges

of the receptacle to force the same against the guide flanges, and a latch formed on the plate for locking the receptacle in place.

2. A sanitary dry closet, comprising a seat, guides on the under side of the seat, opposed flanges on the guides, a receptacle, flanges on the receptacle and adapted to be seated on the flanges of the guides, and a resilient

plate secured to the under side of the seat for pressing the receptacle downwardly and latch it in place. 10

In testimony that we claim the foregoing as our own, we have hereto affixed our signatures.

SILAS ALBERT DIXON.
SAMUEL LYNN RATLIFF.
